DESIGN FOR A MERCHANTISE DISPLAY
RACK

Edward F. Todd, Highland Park, Ill., assignor to
The Imperial Brass Manufacturing Company,
Chicago, Ill., a corporation of Illinois

Application December 20, 1946, Serial No. 135,633

Term of patent 14 years

(Cl. D80—9)

To all whom it may concern:

Be it known that I, Edward F. Todd, a citizen of the United States, residing at Highland Park, in the county of Lake and State of Illinois, have invented a new, original, and ornamental Design for a Merchandise Display Rack, of which the following is a specification, reference being had to the accompanying drawing, forming a part thereof.

In the drawing:

Fig. 1 is a front elevational view of a merchandise display rack, showing my new design, the lid for one compartment of the rack being in open position.

Fig. 2 is a side or end elevational view of the display rack shown in Fig. 1, taken from the right in Fig. 1.

Fig. 3 is a top plan view of the display rack of Fig. 1.

I claim:

The ornamental design for a merchandise display rack, as shown.

EDWARD F. TODD.
